UNITED STATES PATENT OFFICE.

EBENEZER HILL, OF SOUTH NORWALK, CONNECTICUT.

APPARATUS FOR COMPRESSING AIR OR GAS.

SPECIFICATION forming part of Letters Patent No. 593,049, dated November 2, 1897.

Application filed August 17, 1896. Serial No. 602,940. (No model.)

To all whom it may concern:

Be it known that I, EBENEZER HILL, of South Norwalk, in the county of Fairfield and State of Connecticut, have invented a new

5 Improvement in Apparatus for Compressing Gas or Air; and I do hereby declare the following, when taken in connection with the accompanying drawings and the letters of reference marked thereon, to be a full, clear, 10 and exact description of the same, and which said drawings constitute part of this specification, and represent, in—

Figure 1, a plan view of an apparatus constructed in accordance with my invention; 15 Fig. 2, a view thereof in elevation; Fig. 3, a detail view of one of the charging-stands.

My invention relates to an improved apparatus for charging tanks with compressed air or gases, the object being to provide a markedly 20 convenient apparatus which will secure an economy of fuel, labor, and time, but, primarily, which will be adapted to have its air-compressors located at a central station or at substations, according to the dictation of circumstances, to obvious advantage in several 25 ways.

With these ends in view my invention consists in an apparatus having certain details of construction and combinations and arrangements of parts, as will be hereinafter described, and pointed out in the claims, the apparatus being constructed so that any one of its independent air-compressors may be manually turned upon the particular locomotive 30 connected with it or diverted into the system, according to the demands made thereupon at any one time, and so as to help out the other air-compressors in charging the locomotives connected with them.

40 The apparatus chosen for illustration employs three air-compressors A, A', and A'', which may be located at a central station or in different substations, according to the dictation of circumstances. The said air-compressors are connected, respectively, by means 45 of pipes B, B', and B'' with charging-stands C, C', and C'', which are coupled by means of pipes D, D', and D'' to a charging-stand coupling-pipe E, which, as shown, has an air-reservoir F connected with it, though in case the pipe E is very long or in case it is comparatively large in size it may itself constitute a

reservoir of compressed air, in which event the air-reservoir F may be dispensed with. The charging-stands C, C', and C'' being connected together by the charging-stand coupling-pipe E, which makes them interdependent in use, are in one view of them sections or members of a single charging-stand, but inasmuch as they may be in the use of my 55 apparatus widely separated, though coupled, I have chosen to speak of them as individual charging-stands from the fact that each one of them is independently connected with an air-compressor.

60 A detail view of the charging-stand C is shown in Fig. 3, which is illustrative of all of the stands, because they are all alike. This stand comprises valves G and G', which may be of any approved construction, the handle G² of the valve G being connected by a coupling-lever G³ with the handle G⁴ of the valve G'. When the handle G² is operated to open the valve G, the valve G' will be closed, and vice versa. A check-valve H, located above 65 the valve G', permits the current to flow through it only in one direction, which is indicated by the arrow h. The charging-stands are thus seen to have two valved passageways and to constitute a double connection, 70 as it were, between the respective air-compressors and the general apparatus, which is typified by the charging-stand coupling-pipe E. Thus by opening the valve G and closing the valve G' all of the air compressed by the 75 air-compressor individually connected with the stand will be directed into the locomotive connected with the stand, while, on the other hand, by closing the valve G and opening the valve G' all of the air compressed by the compressor connected with the stand will be diverted from any locomotive connected with the stand and into the general apparatus, 80 throughout which the pressure will be raised more or less, according to the pressure in the 85 apparatus at the time and to the pressure of the air diverted.

90 I may here remark that the valves G and G' and the check-valve H may be replaced by a three-way cock, which will perform all 95 their functions and is therefore an equivalent of them, although perhaps not so convenient to use.

100 For convenience of description, as shown

in Figs. 1 and 2, three locomotives I, I', and I², located upon tracks J, J', and J² and respectively connected with the charging-stands C, C', and C² by the locomotive coupling-pipes 5 K, K', and K².

For convenience of describing the operation of my improved apparatus it may be assumed, in the first place, that the locomotive I has just come in to be charged and has been connected by the locomotive coupling-pipe K to the valve G. The handle G² of the said valve is now operated to open the valve G, whereby the valve G' is simultaneously closed. The pressure in the tank of the locomotive, in the 10 compressor A, in the pipe B, in the reservoir F, and in the pipe E will now be equalized by compressed air flowing to the locomotive through the pipe B and thence through the valve G and locomotive coupling-pipe K, and 15 also by compressed air flowing through the pipe D, check-valve H, valve G, and locomotive coupling-pipe K to the locomotive; but the equalization of air, as described, is only temporary, for the air-compressor C, continuing 20 to force air through the pipe B, through the valve G, and through the coupling-pipe K to the locomotive, will raise the pressure in the locomotive above the pressure in the pipes D and E and in the connections thereof, 25 so that the check-valve H will automatically close and prevent any of the air flowing from the compressor A from being deflected into the general system or from going elsewhere than into the locomotive I, the pressure in 30 the tank of which will be gradually raised until the same is fully charged. This then will be the operation of the apparatus as to 35 charging the locomotive I, unless it happens that the action of the compressors A' and A² 40 shall raise the pressure in the charging-stands C' and C², and hence in the pipes D' and D² and pipe E, sufficiently to overcome the pressure tending to keep the check-valve H closed and automatically open the same and contribute 45 to the charging of the locomotive I. When the locomotive I has been charged, the handle-lever G² of the valve G is seized and operated to close the valve G, whereby through the office of the lever G³ the valve G' will 50 be opened, after which the compressed air brought to the charging-stand C from the compressor A through the pipe B, finding no outlet through the valves G or H, will pass 55 through the valve G' and pipe D into the pipe E, so as to raise the pressure therein and in the connections thereof, including the reservoir F. Now if at the time the valve G is closed and the valve G' opened, on account 60 of the completion of the charging of the locomotive I, the locomotives I' or I², either or both, should come in and be connected by means of the pipes K' and K² with the charging-stands C' and C² the air coming from the compressor A will pass through the charging- 65 stand C and thence through the pipe E and its connections to the charging-stands C' and C², through which it will flow into the tanks

of the locomotives I' or I² until the pressure therein is raised by the action of the compressors A' and A², with which the said locomotives are now connected, above the pressure of the air coming from the compressor A, at which time the check-valves of the stands C' and C² will be automatically closed. Then the air compressed by the compressor 70 A' will be utilized to raise the pressure in the reservoir F and the pipe E and the connections thereof. The charging of the locomotives I' and I² will be effected, of course, in the same manner as the charging of the locomotive I, which, if it comes in to be charged after the locomotives I' or I² have been charged, will be assisted in being charged by the air-compressors A' and A², which will make their contribution until its own air-compressor A' has raised the pressure in it 75 sufficiently to close the check-valve H of its charging-stand. 80

It will thus be seen that by employing several air-compressors as many charging-stands 90 having independent connection with the said air-compressors and valved as described or equivalently and means for coupling all of the charging-stands together I am enabled to use all of the compressors all of the time, for 95 when any compressor is not forcing air into the tank of a locomotive connected with its own charging-stand it is assisting the other compressors in charging the locomotives connected with their charging-stands or in raising 100 the pressure in the air-reservoir or in the coupling-pipes of the system, the particular action of any one compressor at any one time being dependent, of course, upon the number 105 of locomotives being charged, the pressure of air in their tanks, and the pressure in the air-reservoir and in the coupling-pipes.

The main advantage resulting from the use of my apparatus lies in its concentration of several air-compressors upon one locomotive and the separation of the compressors, so as to cause them to act individually upon the locomotives directly connected with them, and all this in perfect harmony with the demands put upon the apparatus at any moment, whereby I secure a marked economy of power and the greatest possible despatch. 110 115

It is not necessary, as before stated, that all of the charging-stands should be situated in the immediate vicinity of each other, for, as before suggested, they may be located in widely-separated sections of a city or town, but however located they will all be connected together by the charging-stand coupling-pipe E, which, if long enough and large enough, may be of such great capacity as to itself constitute an air-reservoir and render the use of a special air-reservoir, such as F, unnecessary. 120 125

In its adaptation to have its air-compressors grouped together at a central station or distributed in substations throughout a large area my apparatus secures a great convenience heretofore unattained. 130

The peculiar advantages of my improved apparatus are realized in a measure by employing only two air-compressors and conjunctive accessories, but the effect is increased when three or more are used, and it is very evident from the description and drawings that the apparatus can be indefinitely extended by duplicating the air-compressors and charging-stands and their connections and accessories. I would therefore have it understood that I do not limit myself to the exact construction shown and described, but hold myself at liberty to make such variations therefrom as fairly fall within the spirit and scope of my invention.

Having fully described my invention, what I claim as new, and desire to secure by Letters Patent, is—

1. A charging-stand for use in conjunction with an apparatus for charging tanks, &c., with compressed air or gas, the said stand being adapted to be connected with an air-compressor, and also with one or more similar charging-stands, and containing two independent valved passage-ways, one of which has a check-valve and the other two manual-valves between which the check-valve is interposed.
2. An apparatus for charging tanks, &c., with compressed air or gas, having two or more air-compressors, individual charging-stands connected with the respective air-compressors, and a charging-stand coupling-pipe connected with all of the charging-stands which are adapted to have locomotives connected with them, the valves for the charging-stands being constructed and arranged to per-

mit the compressed air brought to them by their respective compressors to be concentrated upon the particular locomotives connected with them, or diverted into the system, according to the conditions of pressure therein.

3. An apparatus for charging tanks, &c., with compressed air or gas, having two or more air-compressors, individual charging-stands connected with the respective air-compressors, a charging-stand coupling-pipe connected with all of the charging-stands which are adapted to have locomotives connected with them, and an air-reservoir connected with the said charging-stand coupling-pipe, and accumulating compressed air when the same is not taken by the locomotives attached to the stands.

4. An apparatus for charging tanks, &c., with compressed air or gas, having two or more air-compressors, individual charging-stands connected with the respective compressors, and a charging-stand coupling-pipe connected with all of the charging-stands which are adapted to have locomotives connected with them, the valves of each charging-stand being constructed and arranged to concentrate the pressure of its air-compressor upon the locomotive attached to it or to divert such pressure from it to the other stands.

In testimony whereof I have signed this specification in the presence of two subscribing witnesses.
